UNITED STATES PATENT OFFICE.

ANDREW J. SMITH, OF BUENAVISTA, COLORADO, ASSIGNOR OF FIFTY-ONE ONE-HUNDREDTHS TO STEWART M. MILLER AND ERASTUS R. HARPER, OF WHITEPINE, COLORADO.

HOSE-CO尤PLING.

SPECIFICATION forming part of Letters Patent No. 767,843, dated August 16, 1904.

Application filed April 7, 1904. Serial No. 202,009. (No model.)

To all whom it may concern:

Be it known that I, ANDREW J. SMITH, a citizen of the United States, residing in Buenvista, in the county of Chaffee and State of Colorado, have invented new and useful Improvements in Hose-Couplings, of which the following is a specification.

My invention relates to hose-couplings, and has for its object to provide certain new and useful improvements in the construction of the same, as will be hereinafter more definitely pointed out and claimed, reference being had to the accompanying drawings, in which—

Figure 1 is a plan view of the coupling assembled. Fig. 2 is a longitudinal section of the same. Fig. 3 is a detail perspective view of the collar carrying the locking device. Fig. 4 is a similar view of the locking-sleeve.

Similar numerals of reference indicate corresponding parts in the several views.

In the said drawings the reference-numeral 1 denotes one member of the coupling, which may be termed the "female" member, the same having its interior surface 2 tapered to receive the tapered exterior surface 3 of the other member, 4, which may be termed the "male" member. The member 4 is provided on its exterior with a flange 5 and in front of said flange with a lug 6. The member 1 is exteriorly screw-threaded at 7 to receive a sleeve 8, provided with a bayonet-slot 9, adapted to engage the lug 6 when the parts are assembled and by reason of the inclination of said slot to jam the two members together.

Mounted loosely on member 1 to the rear of sleeve 8 is a collar 10, carrying a spring-pressed plunger 11, adapted when said collar is brought in contact with the sleeve 8 to lie in the path of lug 6, said plunger having its end beveled at 12 to permit said lug 6 to be retracted and passed by said plunger when the latter is moving to the locking position, said plunger preventing any movement of the lug in the opposite direction. The outer end 45 of said plunger is formed into a thumb-piece 13 for the purpose of manually retracting said plunger. To the rear of said collar 10 is

a jam-sleeve 14, interiorly screw-threaded to engage the threaded end 7 of member 1.

In practice, with the sleeve 8, collar 10, and jam-sleeve 14 in position on member 1, the member 4 is inserted thereinto until lug 6 engages with bayonet-slot 9, when by rotating the two members oppositely the lug 6 by its engagement with the inclined face of said bayonet-slot will force the two members more firmly together, thus providing a water and air tight connection. In its rotation to position the lug 6 will by contact with the beveled end 12 of plunger 11 retract said plunger to permit the passage of said lug, though when once past said plunger the configuration of the latter will prevent rotation in the opposite direction unless said plunger is manually retracted.

By forming the collar 10, carrying the plunger 11, independent of the sleeve 8 an accurate adjustment of plunger 11 with respect to the bayonet-slot 9 may be obtained, the jam-sleeve 14 maintaining it in any adjusted position.

My invention, while adapted for use in any kind of hose-couplings, is particularly well adapted for use in connection with compressed-air hose-drilling machines and the like, and where the coupling is liable to be dragged over the ground the locking-plunger 11 is particularly useful in preventing accidental uncoupling.

An important advantage attained by forming the sleeve 8 removable from its member 1 is that when the parts become somewhat worn by use said sleeve may be removed from its member independently and refitted to the lug 6 by the average workman.

Having thus described my invention, what I claim as new, and desire to secure by Letters Patent, is—

1. In a hose-coupling, the combination with the two members thereof adapted to engage each other, one of said members having a bayonet-slot therein, and a lug mounted on the other member and adapted to engage said bayonet-slot, of means for engaging and retain-

ing said lug in its locked position against any but positive displacement.

2. In a hose-coupling, the combination with the two members thereof adapted to engage each other, one of said members having a bayonet-slot therein, and a lug mounted on the other member and adapted to engage said bayonet-slot, of an adjustable means for retaining said lug in its locked position against any but positive displacement.
3. In a hose-coupling, the combination with the two members thereof adapted to engage each other, one of said members having a bayonet-slot therein, and a lug mounted on the other member and adapted to engage said bayonet-slot, of a spring-pressed locking-plunger permitting movement of said lug to the locking position, but engaging the same and preventing motion in the opposite direction.
4. In a hose-coupling, the combination with the two members thereof adapted to engage each other, one of said members having a bayonet-slot therein, and a lug mounted on the other member and adapted to engage said bayonet-slot, of a collar adjustable on the slot member, a spring-pressed locking-plunger carried by said collar and permitting move-

ment of said lug to the locking position, but preventing motion in the opposite direction, and a jam-sleeve for retaining said collar and plunger in any adjusted position.

5. In a hose-coupling, the combination of a male and a female member adapted to engage each other, a lug mounted on one of said members, a sleeve mounted on the other member and provided with a bayonet-slot with which said lug engages, a collar loosely mounted on said slot member back of said sleeve, a spring-pressed locking-plunger carried by said collar, lying in the path of travel of said lug in said slot, and having a beveled end adapted to permit the lug to retract it when moving to the locking position, but preventing motion in the opposite direction, and a jam-sleeve engaging said collar to lock it and its plunger in any adjusted position with respect to the bayonet-slot.

In testimony whereof I have hereunto set my hand in the presence of two subscribing witnesses.

ANDREW J. SMITH.
